UNITED STATES PATENT OFFICE

THEODORE J. SCOFIELD, OF JACKSON, MICHIGAN, ASSIGNOR TO THE SPARKS-WITHINGTON COMPANY, OF JACKSON, MICHIGAN, A CORPORATION OF OHIO

ELECTRIC TERMINAL

Application filed May 1, 1929. Serial No. 359,619.

This invention relates to a new and improved electric terminal.

In the construction of electric appliances such as radio sending and receiving instruments and the like, where it is desired to bring one or more wires or other electricity conducting means together at a given point for the purpose of making electrical connection therebetween, it is desirable that such connections be made as easily and quickly as possible and it is also necessary that there be a positive and permanent electrical contact between said means for conducting electricity.

The main object of this invention, therefore, is to construct an electrical terminal which is simply and easily operated and at the same time will obtain a secure grip upon the electricity conducting agencies and insure a positive electrical connection therebetween.

Another object is to provide an electrical terminal which may be constructed at a very low cost and be easily and readily assembled.

A still further object of this invention is to produce a terminal which will be easily and readily adapted to be mounted upon or in connection with various objects when desired to cooperate with said objects or supports to form a positive electrical connection.

Other objects and advantages relate to the details of construction and relation of parts thereof which will more fully appear from the following description taken in connection with the accompanying drawings in

which:—

Fig. 1 is a top plan of a pair of my devices mounted in a common support with one shown in electrical connection with a fixed condenser, while the other one is shown in electrical contact with a suitable ground such as the metal frame of an electrical device.

Fig. 2 is a vertical section taken in the plan of line 2—2 of Fig. 1.

Fig. 3 is a section taken on line 3—3 of Fig. 1, showing the terminal supporting plate and the support therefor.

Fig. 4 is a detail section taken through a possible terminal support and the slot provided therein for the terminal clip and illus-

trating the manner in which they are assembled.

Fig. 5 is a positive view of the terminal clip.

In Fig. 1 of the drawings, I have illustrated a possible manner or method of assembling the electric terminals and it consists of a supporting base plate 1 which is, in this instance, composed of insulating material and may be provided with one or more elongated slots 2, adapted to receive a terminal clip member 3. The terminal clip member 3, in this instance, is constructed from comparatively thin metal and consists of a substantially flat rectangular shaped body portion 4, having the ends thereof enlarged to form laterally extending lugs 5 and 6, projecting outwardly from either side of the body portion 4, to form shoulders 7 and 8 respectively on the inner face of the lugs.

An aperture 9, adapted to receive one or more electricity conducting elements such as a wire or cable as A, Figs. 1 and 2, is provided in the body portion 4 of the clip 3 near one end thereof, while one of the sides of said body portion is cut away near the opposite end thereof to form a V shaped opening or notch 10 for the purpose of facilitating the assembling of the clip with the supporting member coacting therewith. If the supporting base 1 is comparatively thick in cross section as illustrated in the drawings, as is apt to be the case if it is composed of some insulating material the lower portion of the end walls of the slot 2 may be cut away to elongate the slot at the under side of the supporting base 1 as illustrated at 11 to permit the clip 3 to be readily assembled without it being necessary to make the notch 10 of such a size as to weaken the structure of the clip, although this structure may not be necessary when the supporting base 1 is of a relatively thin material in cross section.

In assembling the clip 3 and the supporting base 1, it is only necessary to insert the corner of the end of the clip nearest the notch 10 into the slot 2 with the side containing the notch 10 facing downwardly, then move the clip laterally until the end of the slot 2 registers in the notch 10 as illustrated by dotted lines on Fig. 4. It is now only necessary to rock the clip forward

to the vertical position shown in full lines, whereupon the clip may be lowered until the shoulder 7 rests upon the upper face of the base 1.

- 5 The clip may be yieldingly held in its normal position in the base 1, by a helical spring positioned between the under-side of the support 1 and the lug 6 with the outer end of the spring raising upon the shoulders 8. The 10 spring is assembled in position on the clip by first hooking one end of the spring over the notched end of the clip and then rotate the spring in the direction of the spiral until it moves into position between the lug 6 and the 15 base 1 with the outer end of the spring resting upon the shoulders 8.

In the Figs. 1, 2 and 3 of the drawings, I have illustrated two possible ways of adapting the clip as an electrical terminal. In one 20 of the positions I have illustrated the terminal clip 3 in permanent electrical contact with a fixed condenser 17, while the other position illustrates the terminal clip in permanent electrical contact with a ground such as a portion 25 of supporting frame 18. In the first named position the clip 3 passes through an elongated slot 15 provided in a metal strip 16 and in registration with the slot 2 in the base 1. The metal strip 16 is connected to or 30 integral with one of the plates of the condenser 17 so that by moving the clip forward against the action of the spring 12 until the aperture 9 is positioned above the strip 16, and then inserting a convenient electrical conductor 35 such as a wire or cable A into the aperture 9 and then by releasing the clip 3 the wire will be clasped securely between the clip and strip 16 by the action of the spring 12 as illustrated in Fig. 2.

40 In the other position the electrical connection may be made by the terminal clip between a source of electrical energy and the supporting frame 18, by first inserting a suitable electrical conductor such as a copper wire, 45 into the aperture 9 in the manner as described for the first position, and with the base support 1 supported by the frame 19 as by an angular metallic bracket 19 which has one leg thereof connected to the base 1 and 50 the other leg secured to the frame 18, whereupon the electrical path will be through the clip 3 and spring 12 to the metallic bracket 19, thence to the base supporting frame 18.

55 Although I have shown and particularly described the preferred embodiment of my invention, I do not wish to be limited to the exact construction shown, as various changes may readily be made both in the construction and adaptability thereof, without departing 60 from the spirit of this invention as set forth in the appended claims.

I claim:

1. In an electric terminal, a supporting base provided with a slot, a clip having a body portion adapted to be slidably mounted in

said slot, end portions of greater width than the slot and a notch in one side thereof near one end whereby said clip may be inserted in said slot, and resilient means for tensioning one end portion of said clip in the direction 70 of said base.

2. In an electric terminal, a supporting base provided with a slot, a clip having a body portion adapted to be slidably mounted in said slot, end portions of greater width 75 than the slot, an aperture near one end for receiving an electrical conductor and a notch in one side thereof whereby said clip may be inserted in said slot, and resilient means between said base and the other end of said clip 80 for maintaining said conductor in contact with said base.

In witness whereof I have hereunto set my hand this fifteenth day of April, 1929.
